UNITED STATES PATENT OFFICE.

WILLIAM F. Z. DESANT, OF NEW YORK, N. Y., ASSIGNOR TO THE DESANT ELECTRIC COMPANY, OF OHIO.

ELECTRICAL CONTACT-MAKING DEVICE.

SPECIFICATION forming part of Letters Patent No. 508,871, dated November 14, 1893.

Application filed December 14, 1892. Serial No. 455,143. (No model.)

To all whom it may concern:

Be it known that I, WILLIAM F. Z. DESANT, a citizen of the United States, residing at New York, in the county of New York and State of New York, have invented certain new and useful Improvements in Electrical Contact-Making Devices; and I do hereby declare the following to be a full, clear, and exact description of the invention, such as will enable others skilled in the art to which it app pertains to make and use the same.

The object of my invention is to produce a neat, simple and effective contact making device to be used on rail-roads to operate electric signals or other electrical devices upon the passage of a train or locomotive over said contact making device.

In the accompanying sheet of drawings, Figure 1, is a cross section of a rail with my invention attached, showing a portion of a car wheel passing over the same. Fig. 2, is a detail perspective view of the contact piece. Fig. 3, is a plan view of a portion of a railway track showing the position on the rail which the contact piece preferably occupies.

Throughout the drawings like reference figures refer to like parts.

1, is a track rail.
2, is the contact piece.
3, is the car wheel or a portion of the face and flange of such wheel.
4, is one of the bolts by which the contact piece is clamped to the rail. The bolt 4 has the head 5 and the nut 6.
7, is a sheet of insulating material between the contact piece and the rail acting to completely insulate these two parts one from the other.

8, is a thimble or bushing of insulating material which surrounds that portion of the bolt 4, passing through the web of the rail 1, and insulating it from said rail.

10, is a plate of metal against which the head 5, of the bolt 4, bears, and 9, is a sheet of insulating material which separates this plate 10, from the rail 1.

In Fig. 2, the contact piece 2, is shown in detail in perspective. It has several holes 11, through which the bolts 4, pass, as indicated in Fig. 1.

In Fig. 3, 12, 12, &c., represent the ordinary cross ties on which the rails 1, 13, and 14, are supported. In the usual manner of building rail-way tracks the joints of the rails are not opposite one another but are arranged alternately on either side, as shown in Fig. 3. In many cases it is desirable to have the contact making and breaking device on each side of the track at the same point. In this case my invention would be located as shown in Fig. 3. The rails 13, and 14, would then compose the two parts of one contact device and the rail 1, and the contact piece 2, would furnish the second contact making device. As a pair of car wheels ran along the track they would simultaneously close the contact on either side.

From the foregoing the mode of operation of my invention is clear. In Fig. 1, 15 is the wire and 16, the binding posts connecting the rail 1, with one pole of a battery or other source of electric supply. The wire 17, and the binding post 18, connect the contact piece 2, with the other pole of said source of electric supply. The car wheel 3, always has a face broad enough to over-hang the rail 1, and extend out over and touch the upper face of the contact piece 2. It is clear, therefore, that as the car wheel rolls over the rail it will also touch the contact piece 2, and electrically connect them. Various changes could, of course, be made in the details of the invention without departing from the spirit thereof. In place of the metal plate 10, shown in Fig. 1, the ordinary fish plate could be used. The bolt 4, may be insulated from the contact piece 2, instead of from the rail 1, or to make the insulation doubly secure it might be insulated from both. If, however, the bolt is insulated from one or more of these two elements of the combination it is sufficient to render it operative.

Having, therefore, described my invention, what I claim as new, and desire to protect by Letters Patent, is—

1. In a contact making device the combination of the T shaped rail, the contact piece so shaped on one side as to correspond to the profile of the rail and have its upper face on a level with the top of the rail when the said piece is fitted into place alongside the rail, 95

the sheet of insulating material between the rail and the contact piece and insulated means for fastening said contact piece to the rail, substantially as described.

- 5 2. In a contact making device the combination of the T shaped rail, the contact piece so shaped on one side as to correspond to the profile of the rail and have its upper face on a level with the top of the rail when the said 10 piece is fitted into place alongside the rail, the sheet of insulating material between the rail and the contact piece, the bolts which

pass through the rail and the contact piece and are insulated from one or more of them, and the car wheel whose face is broad enough to reach from the rail to the contact piece and thereby connect them electrically during its passage, substantially as described.

In testimony whereof I affix my signature in presence of two witnesses.

WILLIAM F. Z. DESANT.
